Primary Examiner — Elizabeth Albert(57) **CLAIM**

The ornamental design for a planter reservoir set, as shown and described.

DESCRIPTION

FIG. 1 is a perspective view of the bottom piece of a planter reservoir set without the top piece showing my new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a perspective view of the top piece of the planter reservoir set shown without the bottom piece for convenience; FIG. 8 is a top plan view thereof; and, FIG. 9 is an exploded perspective view of the top and bottom pieces of the planter reservoir set.
